CLAIM

The ornamental design for a beverage dispenser, as shown and described.

DESCRIPTION

FIG. 1 is a perspective view showing the top, front, and right side of the beverage dispenser, showing my new design; FIG. 2 is a perspective view showing the bottom, front, and right side thereof;

FIG. 3 is a front view thereof;

FIG. 4 is a right side view thereof, with the left side view being a mirror image of the right side view; and,

FIG. 5 is a top view thereof.

The broken line(s) in the figures indicate parts of the beverage dispenser which are not part of the claimed design.

1 Claim, 5 Drawing Sheets
